(57)

CLAIM

The ornamental design for a data processing device, as shown and described.

DESCRIPTION

1. Data processing device

1.1 : Front

1.2 : Back

1.3 : Top

1.4 : Bottom

1.5 : Right

1.6 : Left

1.7 : Perspective

1.8 : Perspective

(Continued)

The present design shows a data processing device which is used for industry automation processes.

1 Claim, 8 Drawing Sheets
